DESIGN FOR AN AQUARIUM PUMP

Martin Horowitz, Los Angeles, Calif.

Application December 13, 1947, Serial No. 143,120

Term of patent 3½ years

(Cl. D65—1)

To all whom it may concern:

Be it known that I, Martin Horowitz, a citizen of the United States and resident of Los Angeles, California, have invented a new, ornamental, and original Design for an Aquarium Pump, of which the following is a specification, reference being had to the accompanying drawing, forming part thereof, in which:

Figure 1 is a top perspective view of my aquarium pump showing my new design;

Figure 2 is a bottom perspective view thereof; and

Figure 3 is a top plan view of my aquarium pump.

I claim:

The ornamental design for an aquarium pump, substantially as shown.

MARTIN HOROWITZ.
